MATRIX GRINDING AND MARKING
MACHINE

John E. Sheaffer, Louisville, Ky.

Application May 22, 1939, Serial No. 275,049

12 Claims. (Cl. 51—110)

This invention relates to matrix grinding and marking machines, and more particularly to a machine for reconditioning matrices and marking them for identification so as to be readily distinguished from other matrices which have not been reconditioned.

One object of the invention is to improve generally upon machines of this character so as to secure accuracy and precision in grinding the flat contact portions of the side face of the matrix 10 to effectively remove therefrom the crevices which occur in the use of the matrix and fill with metal in the process of casting in a "Linotype" or other type line casting machine and thereby produce hairlines which give to the printed matter an objectionable fuzzy appearance.

Another object is to provide a practical means of conveying off the gritty particles resulting from the grinding operation and effectively preventing such particles from coming in contact with the working parts of the machine.

With these and other objects to be attained, as will hereinafter more fully appear, the invention consists in the novel general structure and in the particular parts and combinations and arrangements of parts as hereinafter specified and claimed, reference being had to the accompanying drawings illustrating a practical adaptation of the invention, and in which,

Figure 1 is a vertical sectional view of the assembled machine;

Figure 2 is a view of the machine, partly in top plan with the head and certain of the parts carried thereby removed, and partly in section substantially on the line 2—2 of Figure 1;

Figure 3 is an inverted plan view of the head and parts carried thereby, certain parts being shown in horizontal section.

Figure 4 is a top plan view of the machine, on a reduced scale, with parts broken away and removed to disclose interior provisions;

Figure 5 is an inverted plan view of the bottom portion of the machine on the same scale as that of Figure 4;

Figure 6 is a fragmentary section taken on or about the line 6—6 of Figure 1;

Figure 7 is a view partly in elevation and partly in vertical section of the base, intermediate housing portion and head, illustrating part of the suction system for collecting the particles resulting from the grinding operation;

Figure 7^a is a fragmentary view illustrating the application of an auxiliary element in a part of the suction system;

Figure 8 is a fragmentary view of a portion of

the mechanism for actuating and controlling the matrix marking device of the machine;

Figure 9 is a view partly in inverted plan and partly in section on the line 9—9 of Figure 8;

Figure 10 is a fragmentary view partly in top plan and partly in section on the line 10—10 of Figure 8;

Figure 11 is a fragmentary view, on an enlarged scale, illustrating partly in elevation and partly in section, certain parts of the matrix marking mechanism which are directly associated with the saw element;

Figure 12 is a section on the line 12—12 of Figure 11;

Figure 13 is an end view of the driving sleeve for the shaft of the saw element;

Figure 14 is an inner end view of the adjusting element for the shaft of the saw element;

Figure 15 is a cross section through the head of the machine taken substantially on the line 15—15 of Figure 4;

Figure 16 is a fragmentary top plan view with the matrix hopper removed but showing associated parts which cooperate above the matrices which are successively delivered from the hopper to the grinding element;

Figure 17 is a fragmentary view showing the matrix hopper in front elevation and associated parts which control the delivery of the matrices in section;

Figure 17^a is a fragmentary vertical section of the lower portion of the gauge gate which controls the delivery outlet of the matrix hopper;

Figure 18 is a foreshortened bottom plan view of the backing plate for the presser elements which act upon the matrices when the latter are moved from the hopper to the grinding element;

Figure 19 is a section on the line 19—19 of Figure 17, looking in the direction of the arrows; and

Figure 20 is a fragmentary sectional view illustrating details of the adjustable supporting and driving means for the grinding element.

Referring now to the drawings, the numeral 1 designates the base of the machine on which is mounted a body casing or shell 2, a head 3 being mounted on the upper end of said casing or shell 2. Preferably, the opposite side walls of the body casing or shell 2 are relatively thick, as at 2^a, while the arcuate end wall portions are relatively thin, as at 2^b, and made detachable for ready access to the interior of the body or shell as occasion requires. No specific means of fastening the body casing or shell 2 to the base 1 or the head 3 to the casing or shell 2 is shown, as any ob-

vious means of accomplishing this may be employed.

Mounted on a horizontal shelf portion 4 of the base 1 is a conventional electric motor 5 which is utilized for driving a grinding element, certain actuating elements associated with the grinding element, and a blower which is a part of the suction system for collecting the particles of grit and free dust resulting from the grinding operation.

As shown, the grinding element 6, which is in the form of a flat circular disk of abrasive material, having a central opening 7, is mounted on a rotary carrier 8 having an annular supporting flange 9 and a central depression 10, the annular wall portion of said depression being upwardly flared. The bottom plate portion of the depression 10 is provided with a central hub 11 in which is received the reduced upper end portion 12 of the driving shaft 13 of the motor, which shaft, as shown, is a direct extension of the armature shaft of the motor. A portion of the shaft 13, inwardly from its reduced portion 12, is externally screw-threaded to receive thereon an internally screw-threaded sleeve portion 14 of a supporting collar 15 for the hub portion 11 of the grinding element carrier 8. This supporting collar 15 is adjusted longitudinally of the reduced portion 12 of the motor shaft 13 by turning the sleeve portion 14 of the collar on the threaded portion of the shaft 13 and locking the sleeve portion on the shaft by tightening a jam nut 16 on the shaft against the lower end of the sleeve 14. To lock the hub 11 to the supporting collar 15 so that the two parts rotate together, a dowel pin 17 is threaded at one end and secured in the correspondingly threaded opening in the collar 15, the opposite end portion of the pin being received in a smooth bored opening provided therefor in the hub 11. To lock the grinding element carrier 8 against endwise movement relative to the motor shaft 13, a collar 18 is placed about the end portion of the shaft 13 which protrudes above the hub 11 of the grinding element carrier 8, said collar 18 being of substantial thickness which is greater than the normal distance of protrusion of the shaft, said collar 18 supporting a cap disk 19 on its upper end. As shown, the cap disk 19 is provided with a central opening which is upwardly flared to receive therein the tapered head 20 of a retaining screw 21 which is screw-threaded reversely to the threading of the shaft portion on which the sleeve 14 is located, in other words, if there are right hand threads on the shaft, the screw 21 is provided with left hand threads, and vice versa. By this provision the longitudinal adjustment of the supporting collar 15 on the shaft 13 may be readily effected to raise and lower the grinding element to compensate for the wearing down of its upper face and at the same time the grinding element carrier 8 is securely locked against both rotative and endwise movement relative to the shaft 13 after the desired adjustment is effected.

In the structure shown, the collar 15 and its adjacent sleeve portion are afforded a bearing in a cross member 15^a connecting the upper portions of the heavy side members 2^a of the body casing 2, the bearing being provided by counterboring a vertical bore in said cross member 15^a. This cross member 15^a also supports a portion of a housing for the carrier 8 and grinding element 6, which will now be described.

The carrier 8 with the grinding element 6 thereon is housed throughout the entire extent 75

thereof except for a restricted passageway thereabove, through which the matrices are passed successively for the grinding operation thereon, as will be later described, an opening being provided in the housing in communication with ducts which lead to a grit and dust collector also to be later more fully described.

In the particular structure illustrated in the accompanying drawings, the top closure for the housing of the carrier 8 and grinding element 6 comprises a portion of the head 3. The remainder of the housing, designated in general by the numeral 22, follows the general contour of the carrier 8, that is to say, it comprises a generally flat bottom portion underlying and closely adjacent the annular portion 9 of the carrier 8 which supports the grinding element 6 and a central depression which receives the correspondingly formed central portion 10 of the carrier 8 (see Figures 1 and 20). As shown, the depressed central portion of the housing body 22 is formed with an axial opening to receive the lower portion of the hub 11 of the carrier 8, there being a downwardly extended annular flange 23 formed on the bottom of the housing 22 and in which the lower portion of the hub 11 of the carrier 8 is fitted rather snugly but free to rotate therein. The annular flange or collar portion 23 of the housing 22 is received in a counterbored portion of the cross member 15^a, just above the collar 15, by which provision the housing member 22 is held against lineal movement in the plane of its bottom portion and at the same time it is supported on top of the cross member 15^a.

At the marginal portions of the housing bottom 22 are upstanding flanges 24 constituting side walls for the housing, said flanges, as shown, having their upper edge portions received rather snugly in grooves provided therefor in the adjacent top portions of the head 3 (see Figure 15). By this provision the housing 22 may be placed relatively to the motor shaft 13 prior to the installation of the carrier 8 and grinding element 6 and afterward engaged with the adjacent portions of the head 3 when the latter is placed on the body casing or shell 2.

The housing 22 is provided at one side with an outlet opening 25 which establishes communication between the housing and a duct 26 in the head 3, said duct 26, in turn, communicating with a duct 27 formed in the adjacent wall portion of the body casing 2. The duct 27 terminates at its lower end with a flanged port 28 at its inner side, said flanged port 28 being in direct communication with the outer end of a duct 29 formed in a cross member 30 which is suitably supported at its opposite ends on the opposite side members 2^a of the body casing 2.

The inner end of the duct 29 is connected by a short pipe section 31 to the removable head 32 of a cylindrical housing 33 constituting a collector chamber, said housing, as shown, being supported on a raised shelf portion 34 of the base 1 of the machine. This housing 33, as shown, is provided with an axial annularly flanged opening 35, the flange portion being externally screw-threaded and screwed into a correspondingly threaded opening in the shelf portion 34 of the base 1 whereby the housing 33 is held in place and communication is established between the housing 33 and a blower chamber 36 formed in the base 1 just below said shelf 34. It is here noted that the head 32 of the housing 33 is annularly flanged and has a screw-threaded engagement with the housing 33 whereby the

head 32 is readily applied and removed. The short pipe section or nipple 31 is flanged at its lower end to engage the adjacent inner face portion of the head 32, said pipe section 31 being extended upwardly through a central opening in the head 32 and having its upper end portion externally screw-threaded for reception in a correspondingly threaded opening in the cross member 30 for communication with the duct 29, said pipe section 31 being fastened in its adjusted position by a jam nut 37 which is tightened against the adjacent portion of the cross member 30.

Mounted in the blower chamber 36 is the rotor of a conventional blower 38, said blower, as shown, having curved blades 39, said blades being carried by the hub portion of the rotor and extending rearwardly from their ends which are attached to the hub, in relation to the direction of rotation of the element, so that air drawn axially into the chamber 36 through the opening 35 is discharged peripherally through an outlet opening 40 which is arranged substantially tangential to the annular wall of the chamber 36.

The blower chamber 36 is provided with a removable bottom closure 41 having a depressed central portion with an axial opening therein affording a seat for an antifriction bearing 42, the inner member of the bearing supporting the hub portion of the blower rotor 33. The shaft 43 of the rotor 38, designated generally by the numeral 43, has a reduced upper end portion which is screw-threaded to receive a nut 44 by which the rotor is fastened to the shaft 43, said shaft 43 being mounted at its lower end in the inner member of an antifriction bearing 45 which is fitted in the central seat portion of an auxiliary bottom member 46, which latter is detachably secured at its marginal portion to the marginal portion of the bottom closure 41, preferably by the same screw elements 47 which detachably secure said bottom member 41 in place. The auxiliary bottom member 46, as shown, is dished so that ample space is provided between the two bearings 42 and 45 for the accommodation of a pulley 48 which is fastened on the shaft 43 of the rotor 38, said pulley 48 being circumferentially grooved for the reception of a belt 49 which connects said pulley 48 to a driving pulley 50 provided on the lower end of the armature shaft of the motor 5.

For separating the particles of dust and grit from the air stream as it passes through the collector housing 33, a suitable bag 52 of finely woven or porous flexible material permitting the passage of air therethrough but retaining the heavier particles is provided. As shown, this bag 52 is formed to assume a substantially cylindrical shape, that is to say, it has a circular bottom 52^a which is attached marginally to the lower edge portion of a band 52^b, the upper edge portion of the band 52^b being secured to a ring 53 which is formed with an outturned annular flange 54 which may rest either directly upon the upper edge of the housing 33 or, preferably, as shown, upon a correspondingly flanged ring 55 which is interposed between the flange 54 of said ring 53 and the end of the housing 33, said ring 55 carrying a foraminous basket 56 which may obviously be made of open mesh wire fabric or perforated sheet metal, as preferred. As shown, the upper marginal portion of the basket 56 is clamped between the inner flange of the ring 55 and a surrounding band 57, and the lower marginal portion of the cylindrical side wall of

the basket 56 and peripheral portion of the bottom 56' of the basket 56 are joined by an internal ring 58, of angular section, the parts being obviously fastened by a welding process or any other suitable means of fastening such as riveting or the like. In addition to the upper marginal support for the basket, as afforded by the ring 55, an annular supporting ring 59 is mounted in the lower portion of the housing 33 to receive the lower corner portion of the basket 56.

In the normal operation of the machine, as will be later more fully described, the blower sets up a suction in the collector housing 33 and the several ducts which communicably connect the housing 33 with the housing 22 in which the grinding element 6 is located, thereby keeping the housing 22 free of dust and the grit resulting from the grinding operation, thereby preventing loading of the housing 22, and including the central depression in the bottom of the housing 22, as well as preventing the particles of dust and grit from coming in contact with the several working parts of the machine, and thereby minimizing undue wear and injury to said working parts. In this connection, it is pointed out that an internally screw-threaded opening 60 is provided in the outer wall of the duct 27 in the region of its lower end portion where the port 28 thereof communicates with the duct 29, said opening 60 being normally closed by a screw-plug 61 whereby the continuity of the several connecting ducts between the collector housing 33 and the housing 22 of the grinding element is normally maintained. However, provision is made for the exchange of the plug 61 and a nipple 62, which latter may be inserted in the opening 60, as shown more clearly in 7^a of the drawings, said nipple being extended into the lower portion of the duct 27 with the inner end of the nipple in close engagement with the inner wall of the duct so as to effectively close communication between the collector housing 33 and the housing 22 of the grinding element. The nipple 62 is provided at its projecting outer end portion with means for attachment of a conventional coupling 63 of an ordinary hose pipe (not shown) for the application of various vacuum utility appliances when it is desired to use the blower for general cleaning and uses apart from the reconditioning operations on the matrices.

The machine is provided with a matrix feeding magazine or hopper 64 which is in the general form of a channeled vertical column, the longitudinal vertical opening of which is at the rear of the column. The several matrices to be reconditioned are piled flatwise in the magazine or hopper, face to be conditioned downward, with recessed end forward and opposite marginal lugs engaged in the vertical side channels of the magazine or hopper 64 and, with the remainder of the matrix bodies projected rearwardly through the vertical opening of the magazine or hopper. The forward ends of the matrices abut a vertically adjustable gate member 65 comprising an elongated rectangular plate which is fitted rather tightly but slidably in vertical grooves provided therefor in the opposite side walls of the magazine or hopper 64, said gate being frictionally held in vertically adjusted position by a leaf spring 66 interposed between it and the front wall 67 of the magazine or hopper. As shown more clearly in Figure 1, the spring 66 is supported at its middle portion on the wall 67 with its opposite end portions compoundedly curved, as at 68, and pressing continually against the for-

ward face of the gate 65, said spring being fastened to the wall 67 by the same securing screws 69 which secure a spring latch member 70 to the forward face of the wall for a purpose to be presently more fully described.

The bottom matrix in the magazine or hopper 64 is received on a stationary longitudinally elongated plate 71 which extends some distance rearwardly from the magazine or hopper 64 and also forwardly where it terminates near the center of the opening 7 of the grinding element 6, which opening, of course, the forward end portion of said plate 71 overhangs. The gap between the forward end of the matrix receiving plate 71 and the opposite side of the opening 7 in the grinding element 6 is bridged by an auxiliary plate 72 which is placed with its rear end portion in abutting relation to and flush with the adjacent forward end portion of the plate 71 so that the matrices slide without interference from the plate 71 onto the plate 72. Said plate 72 terminates with its forward end portion in close proximity to the adjacent wall portion of the opening 7 in the grinding element 6 and in a plane at least flush with but preferably slightly above the top face of the grinding element 6 so that the matrix traveling on said plate 72 slides freely onto the grinding element 6. As shown in Figure 3, wherein the head 3 is illustrated in inverted plan, the plate 71 is secured at its opposite longitudinal marginal portions to the under side of the top plate of the head 3 by screws 73, the plate 71 covering a slot formed in the top plate of the head 3 and constituting the bottom of a longitudinal slideway the side walls of which guide the matrices as they are moved endwise on said plate 71 to said bridge plate 72. The bridge plate 72 proper, as shown, comprises a rectangular tongue which is formed by slitting the original body blank of the plate rearwardly from its forward end, and on opposite sides of its longitudinal axis, to a transverse line near its rear end and bending the tongue portion so formed downwardly to bring its free forward end into a position relative to the top face of the grinding element 6 as just above described, the rear end portion of the plate 72 being rabbeted to receive the adjacent forward end portion of the plate 71 in the flush relation hereinabove described, and the longitudinal marginal portions of said plate 72 being attached to the head 3 by screws 74 on opposite sides of the slot in the head substantially in the same manner that the plate 71 is attached to the head 3.

The vertically adjustable gate 65 of the magazine or hopper 64 is provided at its lower end with a forwardly extended rightangular foot 75 which is longitudinally slotted on its under side for the accommodation of a forwardly projected normally downwardly set spring tongue 76 which is secured at its inner end to the bottom of the grooved portion of the foot with the head of the screw at least flush with but preferably in clear relief within the groove so as not to interfere with the passage of the respective matrices under the foot 75. The function of the spring tongue 76 is to press the matrix on the plate 71 when the matrix is moved forwardly from the bottom of the pile of matrices in the magazine or hopper 64 and until the matrix so moved is pushed forwardly onto the bridge plate 72 by the next following matrix discharged from the magazine or hopper 64. It is here noted that the gate 65 is of a predetermined length so that when

its lower end portion is positioned in spaced working relation to the matrix receiving plate 71 its upper end portion extends a considerable distance above the magazine or hopper 64 and is formed with a handle portion 77 offset from one longitudinal margin thereof, by which the gate is conveniently manipulated in its vertical adjustment, said gate being also offset from its opposite margin to provide a shoulder 78 which overhangs a shoulder 79 provided on the adjacent end portion of the magazine or hopper 64 to function as a gauge by which the space between the lower end of the gate and the plate 71 is determined. In other words, one of the matrices of a plurality thereof, each of substantially the same thickness, is placed between the shoulders 78 and 79 and the gate 65 is lowered until the shoulder 78 thereof comes in contact with the matrix which is resting on the shoulder 79. With the gate 65 thus positioned and held by the spring element 66, the space between the lower end of the gate 65 and the matrix receiving plate 71 is just sufficient to permit the lowermost matrix of the pile in the magazine 64 to pass freely under the foot portion 75 of the gate 65, yet the matrix next above the bottom matrix is held against movement out of the magazine 64 until the bottom matrix has moved to a position where its rear end is flush with the plane of the inner face of the gate 65.

As the matrices, which are individually designated in the drawings by the numeral 80, travel from the magazine or hopper 64, they pass sequentially beneath the articulated presser elements 81 and 82, said elements 81 and 82 being backed by an elongated generally rectangular retaining plate 83, between which latter and the respective presser elements 81 and 82 are interposed spring elements 84 and 85, said retaining plate 83 being, in effect, also a cover for the slotted portion of the head 3 in which the presser elements 81 and 82 and spring elements 84 and 85 are located, for which purpose the plate 83 is made removable, the outer end portion of the plate 83 being recessed at the opposite corners of its outer end portion, the lug 86 thus formed between said recessed portions being of a width so that it will enter the slot in the head 3 when the inner end portion of the plate is lifted and the outer end portion fulcrums on the beveled undercut shoulders 87 which are formed at the bases of the corner recesses, said plate 83 being held against outward longitudinal movement by a pair of screws 88 which are inserted in the head 3 through the recessed corner portions of the plate 83. Inward longitudinal movement of the plate 83 is prevented by the provision of a pair of lugs 89 at the inner end of the plate 83 which enter an opening in the lower front portion of the magazine or hopper 64 below the lower end of the front wall 67 of the magazine or hopper 64, the corner portions 90 of the plate abutting the adjacent side wall portions of the magazine or hopper 64, by which provision lateral movement of the inner end portion of the plate 83 is also normally prevented. For some distance above the inner end of the plate 83, the lower end portion of the front wall 67 of the magazine or hopper is cut away, as at 91, substantially on a radius from the undercut shouldered outer end portions 87 of the plate 83 so that the inner end portion of the plate 83 may be lifted from its normal closed position by pressing the spring element 70 into the recess provided by the cutaway portion 91 of the front wall 67.

of the magazine or hopper, and for which purpose the plate 83 is notched, as at 92, between the lugs 89 to a depth somewhat greater than that of the corner recesses 90 so as to afford ample clearance for the spring element 70 when the latter is pressed inwardly out of engagement with the adjacent end portion of the plate 83. It is thus obvious that the plate 83 is readily placed in working position and removed, at will.

As shown, the presser element 81 is formed with a major shoe portion 93 beneath which the matrices ride as they move along the plates 71 and 72 and an upwardly offset portion 94 which rests on the foot portion 75 of the gate 65, said upwardly offset portion 94 having a pair of apertures which are loosely fitted to a companion pair of studs 95 projecting upwardly from the foot 75, said apertures being upwardly flared so that the presser element 81 is freely swingable vertically from the foot 75, the spring element 84, however, normally urging the element 81 downwardly into engagement with the bridge plate 72 but being lifted from said plate 72 by the movement of the matrix 80 from the magazine or hopper 64 into engagement with cam faces formed on the under side of the element 81 between the shoe portion 93 and upwardly offset portion 94. The major body portion of the forward presser element 82 is in the general form of a shoe having an upwardly offset inner end portion 96 which is apertured in a manner similar to the offset portion 94 of the element 81 and correspondingly engaged with a pair of upstanding studs 97 provided therefor on the outer end portion of said element 81, on which the offset portion 96 of the element 82 is thus hingedly supported. At the outer end of the presser element 82 is a flange 98 which overhangs a bar 99 extending across the slotted portion of the head 3 in which the element 82 is located so as to limit the downward movement of the presser element 82 under the influence of the spring 85 and thereby prevent the shoe portion of the element 82 from coming in contact with the grinding element 6 when there is no matrix interposed therebetween. This is to prevent marring the under face of the shoe portion of the element 82.

After the grinding operation on the under side of the matrix 80 which is interposed between the forward portion of the grinding element 6 and the presser element 82 thereabove, which operation, of course, occurs during the time the matrix is at rest in the intermittent travel of the line of matrices 80 fed from the magazine or hopper 64 by the intermittent reciprocation of a pusher element to be later more fully described, the dressed matrix is moved from the grinding element by the ejection of the next succeeding lowermost matrix from the pile of matrices 80 in the magazine or hopper 64, said dressed matrix 80 passing through an opening 100 in the forward vertical wall of the housing 22 of the grinding element onto an inclined plate 101 constituting the bottom of a chute through which the matrix 80 is delivered to a drawer or longitudinally movable tray 102, said drawer or tray 102, in its normally retracted position, having its front end wall 103 spaced some distance ahead of a normally spring-retracted follower 104, into which space the dressed matrix 80 is dumped endwise onto the bottom of the drawer or tray 102.

At the forward end of the chute is a gate 105 which is hingedly mounted near its upper end, as at 106, and provided with a spring 107 which yieldably holds the gate 105 in normal closed po-

sition with the lower end portion of the gate 105 disposed vertically above the forward portion of the drawer or tray 102 so as to serve as an abutment for deflecting the matrix 80 into the drawer or tray 102 as the matrix 80 slides down the inclined bottom 101 of the chute. Preferably, as shown, the gate 105 is provided with a notched opening 108 in its lower end portion for the ready reception of a pin-like implement for displacing a matrix 80 should it catch in the chute, and, obviously, the gate 105 may be swung on its pivot 106 to an opened position should it be necessary to thus gain access to the chute. The follower 104 is mounted on the outer end portion of a horizontal reciprocatory bar 109 which is fitted in a guide opening provided in a depending lug portion 110 on the under side of a supporting body portion 111 of the head 3 on which the inclined bottom plate 101 of the discharge chute is mounted. At the inner end of the bar 109 is a head 112, between which and the lug 110 a spring 113 is interposed, said spring normally urging the bar 109 inwardly into engagement with a screw stud 114, which latter is fitted for endwise adjustment in a lug 115 depending from the under side of a reciprocatory actuator 116, said actuator being yieldably held in a normally retracted position by a spring 117, said spring being attached at one end to a stud depending from the under side of the actuator 116 and at its opposite end to an opposed stud depending from the under side of the hereinbefore described cross member 15^a which supports the housing 22 of the grinding element 6 and in which the driving shaft 13 for the grinding element carrier 8 has its bearing. The screw stud 114, as shown, has a tapered outer end portion which is received in a counterpart axial recess in the inner end of the head 112 of the reciprocatory bar 109 which carries the follower 104, by which provision the screw stud 114 not only serves as an adjustable abutment for the bar 109 but the bar 109 may be lifted away from said screw stud 114 intact with the head 3 when the latter is removed from the intermediate body casing or shell 2 of the machine.

Means for intermittently driving the actuator 116 will be later described after the means for ejecting the matrices 80 from the magazine or hopper 64 is set forth. Suffice it to say, at this point, the actuator 116 is operated intermittently and at a time subsequent to the ejection of the lowermost matrix 80 from the pile in the magazine or hopper 64 so as to move the follower 104 forwardly just after a dressed matrix 80 is deposited in the drawer or tray 102, the length of stroke of the bar 109 being such that the initial matrix 80 deposited in the drawer or tray is pressed against the front wall 103 and the drawer or tray 102 accordingly moved forwardly a distance equal to the thickness of the matrix 80, at which time the upper portion of the matrix 80 is moved between an opposed pair of spring tongues 118 which are located on the outside of a pair of side plates 119 (see Figure 2) which are located on opposite sides of the lug 110 in which the bar 109 is slidably mounted. The upper portion of the follower 104, which projects above the side walls of the drawer or tray 102, slides between said side plates 119 and the dressed matrix obviously drops between these plates 119 as it is delivered onto the bottom of the drawer or tray 102. In this connection, it is noted that the forward upper portions of the side plates 119 are cut away or foreshortened to afford

clearance for inwardly offset free end portions 120 of the spring tongues 118, said offset portions 120, in the normally retracted position of the drawer or tray 102, being disposed in engagement with the opposite sides of the front wall 103 of the drawer or tray 102 whereby the tongues 118 are sprung outwardly, but as soon as the wall 103 is moved forwardly with the dressed matrix 80 pressed thereagainst by the follower 104 said inwardly offset portions 120 of the tongues, by the reaction of the tongues, press against the upper marginal portions of the matrix 80 and thereby hold the matrix 80 in its vertical relation to the wall 103, it being here noted that the bottom of the drawer or tray 102 is provided on opposite sides with longitudinal series of serrations or otherwise roughened to resist any tendency of the lower end of the matrix to move away from the wall 103. In this connection, it is pointed out that the forward portions of the plates 119 serve as stops for limiting the inward movement of the spring tongues 118 so that the inwardly offset portions 120 of the tongues function in their yieldable retentive capacity relative to the dressed matrix 80 deposited in the drawer or tray 102, yet do not interfere with the positioning of the matrix 80 against the end wall 103 of the drawer or tray under the pressure of the follower 104.

In the continued operation of the machine the respective matrices after they are successively dressed are deposited sequentially behind the line of preceding matrices 80 in the drawer or tray 102, the rearmost matrix 80 in the line being obviously engaged by the inwardly offset portions 120 of the spring tongues 118 due to the intermittent actuation of the follower 104, the length of stroke of which latter may be constant, but the relative retracted position of the follower 104 may be varied with respect to the inner face of the wall 103 of the drawer or tray 102 by adjusting the screw stud 114 longitudinally in its supporting lug 115. As shown, the drawer or tray 102 is frictionally held in its various longitudinal positions by a spring element 121 mounted in the forward portion of the slideway in which the drawer or tray works, said spring 121 pressing against the bottom of the drawer or tray 102.

The means for ejecting the matrices 80 from the magazine or hopper 64 will now be described. As shown, this particular mechanism comprises an elongated rectangular pusher plate 122 which is mounted with its forward end portion slidably overlapping the rear end portion of the plate 71 which receives the lowermost matrix 80 of the pile in the magazine or hopper 64, the forward end of the pusher plate 122, in the normal retracted position of said plate 122, terminating just short of the end portion of the matrix 80 which it abuts. Above the pusher plate 122 is a cap plate 123, the rear end portion of which overlaps the adjacent top face of the head 3, where it is secured to the head 3 by screws or other suitable fasteners 124, the forward end portion of said cap plate 123 being similarly fastened to the head 3, as at 125, whereby said plate 123 is readily removed and replaced, at will. Said plate 123 is formed with a downwardly offset shoe 126 which is fitted in the slideway of the pusher plate 122 and is disposed relatively above the forward portion of said plate 122 which slides between the shoe 126 and the adjacent underlying end portion of the matrix receiving plate 71. As shown, the upper portion of the shoe 126 is formed with an open-ended re-

cess 127 whereby access to the matrices 80 at the bottom of the pile in the magazine or hopper 64 is conveniently had should occasion require. The rear end portion of the pusher plate 122 is supported on and attached to the forward end portion of a reciprocatory carriage 128 which slides in oppositely disposed guideways 129 provided therefor on the under side of the top body plate of the head 3, said guideways 129 being attached to the head 3 by a plurality of screws or other suitable fasteners 130. The carriage 128 is provided with a depending post 131 of substantial body and rigidity, at the lower end of which is a roller 131' engaging the periphery of a cam plate 132 when the carriage 128 is moved forwardly under the influence of a spring 133 during the rotation of the cam plate 132, said spring 133 being secured at one end to the under side of said body plate of the head 3, as at 134, the opposite end of the spring 133 being attached to one end of a rocking lever 135 which is pivotally attached to the head 3, as at 136. The opposite end of the lever 135 is hingedly connected to the forward portion of the carriage 128 by a link 137 whereby reciprocatory movement is imparted to the carriage by the oscillation of said lever 135. The carriage 128 is provided with an opening 138 in its rear portion which is engaged by a spring latch element 139 for releasably holding it in a retracted position, said spring latch 139 being attached to the head 3, as at 140, and with a normal set whereby its hooked free end portion 139' is directed toward the body plate of the head 3 with the distance therebetween regulated by an adjusting screw 141 which normally impinges the bracket by which the latch element is attached to the head 3 or any other obvious abutment provided for the purpose. By this form and arrangement of the spring latch 139, said latch 30 automatically engages in the opening 138 of the carriage 128 when the latter is manually retracted, for which purpose the depending post 131 is provided with a screw-threaded axial stud extension 143 at its upper end, said stud portion 143 being fitted in a screw-threaded opening provided therefor in the carriage plate 128 and a locking nut 144 being applied on the stud portion 45 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

As above described, the spring element 133, through its lever and link connection with the carriage 128, acts to drive the matrix ejector 122 forwardly when permitted by the cam 132 against the periphery of which the roller 131' on the post 131 of the carriage 128 is at all times in contact except when the carriage 128 is manually retracted and held by the spring latch 139. The body plate of the cam 132 is provided with an

opening which is fitted rotatably on an enlarged upper portion of a spindle sleeve 147, said spindle sleeve 147 being fitted rotatably on an up-standing supporting post 148. As shown, the supporting post 148 is provided at its upper end with a head for retaining the spindle sleeve 147 on the post, and the post having a reduced lower end portion fitted in an opening provided therefor in the transverse body portion 30 of the housing of the machine (see Figure 1), the distance between the retaining head at the upper end of the post 148 and the annular shoulder at the base of its reduced lower end portion being such that the spindle sleeve 147 is free to rotate on the post 148 without any binding effect or undue resistance at the ends of the sleeve, while the extreme lower end portion of the reduced extension of the post 148 is screw-threaded for the reception of a locking nut 149, which latter is tightened against the under side of the transverse body portion 30.

While the cam plate 132 is fitted to the spindle sleeve 147 so that the one element may rotate independently of the other element, should occasion require as will hereinafter more fully appear, provision is made for normally rotating the cam plate 132 with the spindle sleeve 147 by forming a ratchet head 150 on the upper end of the spindle sleeve 147 and providing the cam plate 132 with a pivotally mounted dog 151 on its top face, said dog 151 having a lug 152 which is engaged by one of the ratchet teeth on the head 150 in the normal position in which the dog 151 is yieldably held by a spring element 153. That is to say, the cam plate 132 rotates with and by the spindle sleeve 147 in one direction with a positive drive during the normal operation of the machine.

The spindle sleeve 147 is provided with a driving gear 154 having counterpart teeth on its periphery which intermesh with a worm screw 155 on a driving shaft 156 which is conventionally mounted in bearings 157 in working relation to the gear 154, said driving shaft 156 being provided at one end with a miter gear 158 which is in engagement with a correspondingly beveled gear 159 which is adjustably mounted on the motor shaft 13 and secured in its adjusted position by a set screw 160 (see Figure 20). The driving gear 154 is mounted on the spindle sleeve 147 with frictional engagement therebetween so that, normally, the gear 154 and sleeve 147 are rotatable by and with each other, but with safety slippage should undue resistance be brought to bear upon either the gear 154 or sleeve 147 and thereby prevent damaging said elements or any of the associated elements in the operating mechanism of the machine.

A companion spur gear 161 is mounted with the gear 154 on the spindle sleeve 147, said gear 161 being provided primarily for driving a matrix marking element to be later more fully described. As shown, the two gears 154 and 161 are fastened together so as to rotate as one, the fastening being by any suitable means but preferably by a screw 162 or a plurality thereof located at intervals throughout the extent of the gears (see Figure 1). The frictional engagement between said gears 154 and 161 and the spindle sleeve 147 may be effected in any conventional manner, such for example, by interposing friction rings 163 between the hub portions of the gears 154 and 161 and the annular shoulder provided at the base of the enlargement of the spindle sleeve 147 on which the cam plate 132 is mounted, the clamping

of the friction rings 163 being effected by adjusting a collar 164 on the screw-threaded lower end portion of the spindle sleeve 147 in abutting relation to the under side of the gear 154 and locking said collar 164 in adjusted position by a set screw 165. It will thus be seen that the interfastened gears 154 and 161 are driven positively by the worm 155 with which the gear 154 is in mesh, the shaft of said worm 155 being driven directly from the motor shaft 13, while, as hereinbefore described, the cam 132 is rotated normally by the engagement of its dog 151 with the ratchet head 150 of the spindle sleeve 147, which latter is in turn driven by the frictional engagement between it and the interfastened companion gears 154 and 161. In this connection, it is here noted that inasmuch as the cam 132 also actuates the reciprocatory actuator 116 which is operated intermittently to reciprocate the follower 104 so as to effect a step-by-step forward movement of the drawer or tray 102 as the dressed matrices 80 are deposited therein, the peripheral contour of the cam plate 132 is necessarily such that the ejector plate 122 may overtravel on its matrix ejecting stroke, and in order to prevent this happening a special stop 166 is provided to arrest the movement of the rocking lever 135 under the influence of the spring element 133 (see Figure 3), said stop 166, for the purpose of adjustment, being in the form of a headed screw which is threaded into a supporting lug 167 provided therefor on the adjacent under portion of the head 3 of the housing body of the machine.

As shown, the reciprocatory actuator 116 is carried by a rod 168 which is mounted to slide longitudinally in a portion of the transverse body member 15^a which supports the housing 22 and carrier 8 of the grinding element 6. The end of the rod 168 opposite to that on which the actuator 116 is carried is bifurcated, as at 169, and has a roller 170 journaled therein.

In the normally retracted position of the actuator 116, to which position said actuator 116 is moved and yieldably held under the influence of the spring 117, the roller 170 is located in the path of the high side of the cam 132 and at a relative distance from the axis of the spindle sleeve 147 so that, when said roller 170 is engaged by the rotating cam 132, at a time subsequent to the matrix ejecting stroke of the ejector plate 122, the actuator 116 is moved forwardly a predetermined distance to effect a corresponding movement of the follower 104 to press the last deposited dressed matrix 80 to an up-ended vertical position and thereby move the drawer or tray 102 one step forward to make room for the next following dressed matrix 80. In this connection it is noted that, in order to afford ample clearance for the aforesaid actuation of the actuator 116, the adjacent portion of the body 15^a is recessed, as at 171, to receive the bifurcated end portion 169 of the rod 168.

Inasmuch as it may be necessary, from time to time, to stop the operation of the cam plate 132, provision is made for effecting the disengagement of the dog 151 on the cam plate 132 from the driving ratchet head 150 of the spindle sleeve 147. For the accomplishment of this the dog 151 is provided with a lateral extension 172 which is recessed, as at 173, on its leading side in the direction of normal rotation of the cam plate, said recessed portion 173 being engageable with a dog 174 which is normally out of the orbit of said recessed portion but is movable into the path thereof to arrest the movement of the cam plate 132,

at will. As shown, the dog 174 comprises an arm of a bellcrank which is pivotally mounted, as at 175, on a stationary support 176 which constitutes part of a detachable unit which is mounted on the cross body member 30 of the machine housing, said body portion 30 being provided with an open-ended slot 177 for the reception of a securing stud 178 on the lower end of the support 176, said stud 178 being screw-threaded to receive a clamping nut 179 which is tightened against the under side of the adjacent portion of the body member 30, it being here noted that the detachable unit of which the support 176 is a part includes principally the matrix marking means to be presently described. The opposite arm 180 of the aforesaid bellcrank constitutes a handle for the manual manipulation of the dog 174 in swinging the latter into and out of its normal disengaging relation to the arm 172 of the dog 151, the bellcrank being frictionally held in its normal and operated positions by a spring 181 which is coiled about the pivot stud 175 on which the bellcrank is mounted, said spring 181 being interposed under compression between the under side of the bellcrank and a head formed at the end of the stud 175.

Obviously, in the normal position of the dog 174, out of the path of the notched end portion of the arm 172 of the dog 151 on the cam plate 132, said cam plate is free to rotate with the spindle sleeve 147 as hereinbefore described, but when the dog 174 is swung into the path of the notched end portion of the arm 172 of said dog 151 the engagement of the arm 172 with the dog 174 causes the dog 151 on the cam plate 132 to swing out of engagement with the ratchet head 150 of the spindle sleeve 147 against the retractive action of the spring element 153, the movement of the dog 151 out of engagement with said ratchet head 150 being arrested by a stud 182 projecting upwardly from the top face of the cam plate 132 in the path of a notch 183 formed in the marginal portion of the arm 172 of the dog 151. With the dog 151 thus disengaged from the ratchet head 150 and its arm 172 engaged with the dog 174 and locked against the stud 182, the cam disk 132 is, of course, held against movement in the direction in which it was rotating with the spindle sleeve 147, and the spindle sleeve 147 continues its rotation due to its frictional engagement with the driving gear 154.

In order to establish a frictional engagement between the cam plate 132 and the interfastened driving gears 154 and 161, so as to prevent a reverse rotation of the cam plate 132 after the disengagement of the dog 151 from the ratchet head 150 is effected as just above described, the cam plate 132 is provided on its under side with a circular disk 184 which is dished so as to provide an annular trackway 185 at its periphery, against which the head of a spring-pressed plunger 186 (or a plurality thereof) carried by the interfastened gears 154 and 161 bears (see Figure 1), it being understood that the spring element constantly urges the plunger 186 upwardly into contact with the trackway 185 and that the strength of the spring is sufficient to create ample frictional resistance between the head of the plunger and the trackway to overcome the reactive effect of the spring element 153 which, through the leverage of the dog 151 with its notched end portion 173 as the fulcrum when engaged with the dog 174, would cause the cam plate 132 to rotate in the direction opposite to that of its normal operative rotation and 75

thereby effect a re-engagement of the dog 151 with the ratchet head 150 intermittently and at least causing annoyance if not injury to certain working parts if such provision for the aforesaid frictional engagement between the cam plate 132 and the driving gears 154 and 161 is not made.

An essential feature of the present invention is the provision of means for marking the matrices 80, which marking is preferably accomplished successively on the respective matrices 80 at a time after they have been ejected from the magazine or hopper 64 and prior to the dressing of the matrices on the grinding element 6. This means will now be described. As shown, 15 the marking element comprises a circular saw blade 187 which is carried on the end of a spindle 188, said spindle 188 being rotatably mounted on a supplemental support, designated generally by the numeral 189, which is swiveled on 20 the hereinbefore described unitary support 176 which also carries the hereinbefore described dog 174 which is correlated to the releasable driving elements of the cam plate 132. As shown, the support 189 is provided with a bearing 190 (see Figure 11) in which the main body portion of the spindle 188 is directly journaled, the spindle 188 having a reduced axial extension 191 the outer end portion of which is screw-threaded to receive a combined adjusting and bearing element 192, said element 192 being of general cylindrical form with a screw-threaded axial bore to fit the threaded portion of the extension 191 of the spindle 188, the inner portion of said element 192 being journaled in a bearing portion 35 193 of the supplemental support 189 in opposed relation to the aforesaid bearing 190 of said support 189, the outer portion of said element 192 being enlarged and preferably knurled on its periphery to constitute a knob 194 for conveniently manipulating said element 192 in effecting an endwise adjustment of the spindle 188 as will presently more fully appear. Sleeved on the spindle 188 and interposed between the journal portions 190 and 193 of the support 189 is the 40 axially bored body portion 195 of a spiral gear 196, the bore of the body portion 195 being of a general diameter throughout approximately the entire length thereof to receive the main body portion of the spindle 188 with a sliding fit, said 45 spindle portion, adjacent its reduced extension 191, being provided with a longitudinal groove 197 to receive a spline 198 on the body portion 195 of the spiral gear 196, said spline 198, as shown, being in the form of a screw the inner end of which is projected into said groove 197 of the spindle whereby the spindle is movable longitudinally in the body portion 195 of the gear 196 but is keyed to rotate with the latter. A 50 spring element 199 is coiled about the reduced extension of the spindle 188 within the bore of the body 195 of the gear 196, said spring abutting at one end against the annular shoulder at the base of the reduced portion 191 of the spindle and at its opposite end against a shoulder 55 provided at the adjacent end of the body 195 by a reduction in the bore of the body 195 to a diameter just slightly larger than that of the reduced portion 191 of the spindle so that the latter may slide freely endwise therethrough, the 60 spring element 199 being constantly under compression and reacting to urge the spindle 188 forwardly to position the saw 187 and to hold the combined adjusting and bearing element 192 in engagement with the adjacent end of the 65 cylindrical body 195 of the spiral gear 196. The 70 75

engagement between the body portion 195 and the element 192 is interlocked so that the one part rotates by and with the other but at the same time it is releasable to effect adjustment of the spindle, for which purpose the adjacent end portion of the body 195 is enlarged to provide an annular collar 200 which abuts the inner side of the journal portion 193 of the support 189 and the end face of the body 195 is provided with a radial recess 201 of generally rectangular form to receive a correspondingly shaped lug 202 provided on the inner end of the adjusting and bearing element 192. By this provision it is obvious that the element 192 rotates normally with the spiral gear 196 but is retractable so that its lug 202 is disengaged from the recess 201 in the body 195 of the gear and that by manually rotating the element 192 so disengaged the spindle 188 is accordingly moved endwise by reason of its splined relation to the gear 196, which latter may be held against rotation either by manually holding it against such movement or due to its engagement with the peripherally toothed driving gear 203 to be now described in connection with the operating and controlling mechanism for the saw spindle 188.

The driving gear 203 is pinned or otherwise secured on a vertical shaft 204 which is suitably journaled at its opposite ends in the stationary main support 176 of the unit, said shaft having a pinion 205 pinned or otherwise secured on the lower portion thereof in mesh with the driving gear 161 which, as hereinbefore described, is companion to the gear 154 and to which it is interfastened so as to rotate therewith when the spindle sleeve 147 to which said gears 154 and 161 are frictionally engaged is rotated. Thus the saw spindle 188 is constantly rotated during the normal operation of the machine. However, the spindle 188 is intermittently oscillated in a horizontal plane to bring the saw 187 into and out of cutting position for marking the respective matrices 80 in timed relation to the intermittent feeding movement of the matrices 80 to the grinding element 6. For this purpose, the supplemental support 189 is supported to swing about the axis of the shaft 204 on a shelf-like portion 206 of the stationary main support 176, an adjustable stop, comprising a screw 207 mounted on the support 176, limiting the swinging movement of the spindle 188 away from the trackway along which the matrices are moved to the grinding element 6, and a fixed shoulder 208 being provided on said support 176 for limiting the maximum movement of the spindle 188 towards said trackway.

The saw spindle 188 is normally urged toward the matrix trackway by a spring 209 which is attached at one end to a stud 210 which is projected from the side of the stationary main support 176 and at its opposite end to the supplemental support 189, as at 211, the spring 209 being thus offset from the shaft 204 whereby ample leverage is afforded to swing the support 189 about the axis of said shaft 204. As just above described, the maximum movement of the saw spindle 188 toward the matrix trackway is limited by the fixed shoulder 208 which is engaged by an opposed edge portion 208' of the support 189, but in the normal operation of the machine this particular movement of the spindle 188 is limited by a circular disk 212 which is carried by the cam plate 132 with the axes of the disk 212 and the spindle sleeve 147 coinciding, the larger portion of the periphery of the

disk being concentric with the axis thereof and the remainder of the periphery being recessed arcuately, as at 213. This disk 212, although it rotates with the cam plate 132, is spaced above the ratchet head 150 of the spindle sleeve 147, it being fastened to a plate-like bracket 214 which is offset upwardly from a marginal supporting flange 215 which is detachably secured to the top face of the cam plate 132 by screws 216. For adjusting the disk 212 to set its recessed portion 213 in correlated timed working relation to the feeding operations of the matrices 80 as effected by the cam 132, the disk 212 is secured to the bracket plate 214 by a screw 217 which is inserted from below through an aperture in the bracket plate 214 and into a threaded axial aperture in the disk 212, the aperture in the bracket plate 214 being preferably flared so that the tapered head of the screw 217 is countersunk therein, thus leaving the under side of the bracket plate 214 without any protuberance which might interfere with the normal operation of the spindle sleeve 147 and said cam plate 132. The swiveled supplemental support 189 is provided with an end extension 218 which is downwardly offset and provided with a horizontal opening in which a screwthreaded shank 219 is received so as to be adjusted longitudinally therein, said shank 219 being locked in its adjusted position by jam nuts 220 which are tightened against the opposite sides of the extension 218. Said shank 219 is bifurcated at one end, as at 221 and has a roller 222 journaled therein, said roller 222 being held in contact with the periphery of the disk 212 under the influence of the spring 209, the concentric peripheral portion of the disk 212 holding the spindle 188 with the saw 187 normally away from the adjacent longitudinal portion of a matrix 80 on the trackway and the recessed portion 213 rounded arcuately, as it is, permitting the saw 187 to be eased gradually into cutting relation to the positioned matrix 80 and likewise moved therefrom when the roller 222 rides into and out of the recess 213 during the rotation of the disk 212 which, normally, is simultaneous with the rotation of the cam plate 132 but in timed relation to the movement of the matrices 80 from the magazine or hopper 64 as just above described.

While the above described oscillation of the supplemental support 189 continues intermittently during the normal operation of the machine, provision is made for placing the saw 187 in an inoperative position, at will, and releasably holding it in such position. The means for accomplishing this comprises a puller bar 223 which is pivotally attached, as at 224, to the under side of the end extension 218 of the swiveled supplemental support 189 (see Figure 9), said puller bar 223 being projected through an opening 225 provided therefor in the side wall 2a of the body housing and having a hooked end portion 226 by which the bar 223 may be conveniently grasped for manual manipulation. Normally, this bar 223 reciprocates longitudinally when the saw spindle 188 is oscillated during the operation of the machine, the outermost position of the bar 223 being controlled by the position in which the saw spindle 188 is placed by the engagement of the roller 222 with the concentric major portion of the disk 212. However, by pulling the bar 223 outwardly the swiveled support 189 is swung correspondingly about the axis of the shaft 204 and against the tension of the spring element 209, the bar 223

becoming automatically locked against return movement by the notched arm 227 of a bell-crank latch element engaging with its shoulder portion 228 against the adjacent outer face portion of the wall 2^a, into which engaging relation the latch element is moved by a spring 229 connecting its opposite arm 230 with a stud 231 provided on the end extension 218 of said swiveled support 189. Normally, the arm 227 of the bellcrank latch element reciprocates with the bar 223 in the opening 225 in the side wall 2^a, the length of stroke being obviously such that the shoulder 228 of the arm 227 remains within the opening 225 during this normal reciprocation of the parts. To limit the outward movement of the saw spindle 188 by the manual operation of the pulley bar 223, the hereinbefore described adjustable stop 207 is provided on the stationary main support 176, said stop 207 being engaged by a shoulder 207' formed on the opposed end portion of the swiveled supplemental support 189 (see Figure 10), this provision being primarily for the prevention of damaging the saw 187 or marring the adjacent body portion or working part of the machine in the region where the saw 187 operates.

In summarizing, in the general operation of the machine the matrices 80 to be conditioned are piled in the magazine or hopper 64, side to be dressed downward, the gate 65 having been adjusted with the space between its lower end and the matrix receiving plate 71 in accordance with the thickness of an individual matrix of a particular font or set thereof. With the various adjustments of the several working parts effected as hereinbefore described, and the motor 5 in operation, the ejector 122 reciprocates to eject the matrices 80 one at a time from the bottom of the pile in the magazine or hopper 64 and intermittently moves a line of the ejected matrices 80 along the trackway from the magazine or hopper 64 to the grinding element 6, the matrices 80 traveling under the articulated spring-pressed shoes 81 and 82, and the travel of the matrices 80 from the magazine or hopper 64 being intermittent or in a step-by-step process, the marking saw 187 is moved through an opening 187' in the side of the trackway into cutting engagement with the respective matrices 80 during a period of rest thereof at a place between the magazine or hopper 64 and the operating portion of the grinding element 6, whereby the marginal portions of the matrices 80 are nicked for the purpose of indicating that they have been reconditioned. The dressed matrices 80 are delivered from the grinding element 6 into the drawer or tray 102 as hereinbefore described, whence they are removed in a finished set from the drawer or tray and a new font may be then passed through the machine. In this connection, it is here noted that, in the usual operation of the machine, duds or dummy matrices in sufficient number are passed through the machine behind the string of regular matrices to clear the machine of the entire font or set of the latter after the grinding operation is completed.

During the operation of the grinding element 6 the blower 38 is operating simultaneously therewith, thereby creating an effective suction in the collector shell 33 and the ducts which provide a closed passage between the shell 33 and the housing 22 of the grinding element 6 whereby the gritty detritus and free dust is drawn off so as to prevent loading of the grinding element 6 and its housing 22 whereby the operation of the

grinding element 6 continues efficiently and at the same time the several working parts of the machine are effectively guarded against damage which would otherwise result from the gritty particles coming in contact therewith. Obviously the filter bag 52 effectively separates the heavier particles from the air stream, said bag being removed from time to time and cleaned. In this connection it is further pointed out that by applying the special nipple tube 62 in place of the removable plug 61 and coupling an obvious vacuum cleaner attachment thereto the blower 38 and collector 33 may be utilized for various extraneous cleaning purposes, at which time, of course, the ducts between the collector 33 and the housing 22 of the grinding element 6 are closed against communication between said housing 22 and the collector 33 and it being further understood that the machine is not at the time in operation for the reconditioning of the matrices.

From the foregoing it is apparent that a practical and highly efficient machine is produced primarily for the reconditioning of matrices, with the adjuncts above noted, and while the machine illustrated in the drawings embodies a practical adaptation of the invention it is obvious that considerable modification may be made therein without departing from the spirit and scope of the invention as defined by the appended claims. The invention, therefore, is not limited to the specific construction and arrangement shown in the accompanying drawings.

What is claimed is:

1. In a machine for reconditioning matrices, a horizontally rotating, flat-surfaced annular grinding element, a correlated trackway above said grinding element over which the respective matrices to be reconditioned are passed successively onto the grinding element, a vertical open-bottomed magazine for initially receiving the matrices in a pile therein, the bottom matrix of the pile resting on said trackway, motor-driven mechanism for rotating said grinding element, means including an intermittently operable reciprocatory ejector device operating with the rotating mechanism of said grinding element in timed relation thereto for successively moving the matrices along the trackway from the magazine and onto the grinding element, means for individually marking the respective matrices when in a definite common position during a period of rest as they are passed along the trackway from the magazine, said marking means including a rotary saw mounted to move laterally towards and from the trackway to engage and disengage each successively positioned matrix marginally thereof, and actuating means for said saw operating with and in timed relation to the mechanism which rotates the grinding element and oscillates said ejector device.

2. In a machine for reconditioning matrices, a horizontally rotating, flat-surfaced annular grinding element, a correlated trackway above said grinding element over which the respective matrices to be reconditioned are passed successively onto the grinding element, a vertical open-bottomed magazine for initially receiving the matrices in a pile therein, the bottom matrix of the pile resting on said trackway, motor-driven mechanism for rotating said grinding element, means including an intermittently operable reciprocatory ejector device operating with the rotating mechanism of said grinding element in timed relation thereto for successively moving

the matrices along the trackway from the magazine and onto the grinding element, means for individually marking the respective matrices when in a definite common position during a period of rest as they are passed along the trackway from the magazine, said marking means including a rotary saw mounted to move laterally towards and from the trackway to engage and disengage each successively positioned matrix marginally thereof, actuating means for said saw operating with and in timed relation to the mechanism which rotates the grinding element and oscillates said ejector device, and manually operable means for selectively rendering said ejector device and the marking saw individually inoperative, at will.

3. In a machine for reconditioning matrices, means including trackage for successively passing the matrices lineally to a grinding element with intermittent travel, means for individually marking the respective matrices during a period of rest in the travel thereof, said marking means comprising a rotary saw mounted on the free end of a spindle mounted for oscillation relative to the trackage for said intermittently traveling matrices, power means for rotating said spindle, means for moving and holding the spindle in its oscillation away from the line of matrices during the travel of the latter, and means for moving the spindle toward the line of matrices and the saw into marginal engagement with a positioned matrix during the period of rest in the intermittent travel of the matrices.

4. In a machine for reconditioning matrices, means including trackage for successively passing the matrices lineally to a grinding element with intermittent travel, means for individually marking the respective matrices during a period of rest in the travel thereof, said marking means comprising a rotary saw mounted on the free end of a spindle mounted for oscillation relative to the trackage for said intermittently traveling matrices, power means for rotating said spindle, means for moving and holding the spindle in its oscillation away from the line of matrices during the travel of the latter, means for moving the spindle toward the line of matrices and the saw into marginal engagement with a positioned matrix during the period of rest in the intermittent travel of the matrices, and manually operable means for retracting said spindle and releasably holding it in an oscillated position away from the line of matrices with the saw clear of the matrix in the region thereof.

5. In a machine for reconditioning matrices, including trackage on which the matrices are moved successively and intermittently in a line to a grinding element, means for individually marking the respective matrices during a period of rest in the travel thereof, said means comprising a rotary saw mounted on the free end of a spindle which is mounted to oscillate toward and from the trackage of said intermittently traveling matrices, said spindle having provision for longitudinal adjustment thereof in its mounting, means for constantly rotating said spindle, means for intermittently oscillating said spindle during its rotation and in timed relation to the intermittent travel of the matrices whereby to move and hold the spindle with the saw out of engaging position relative to a matrix traveling in the region thereof and to move the spindle reversely to engage the saw marginally with a positioned matrix during the period of rest in the travel thereof, and means for manually retracting said

spindle and releasably holding it with the saw out of engagement with the matrix in the region thereof.

6. In a machine for reconditioning matrices, including a grinding element over which the matrices to be reconditioned are passed successively with intermittent travel in a line from trackage interposed between the grinding element and a receiving magazine, a reciprocatory ejector device for moving the matrices one at a time from the bottom of a pile thereof in the receiving magazine of the machine, means for releasably holding said ejector device in retracted position, spring-actuated impelling means for moving said ejector device in the direction to eject a matrix from the magazine, means for positively moving the ejector in its retractile direction, said last-named means including a rotating cam against the periphery of which an anti-friction bearing element of the ejector device is held under the influence of the spring-actuated impelling means of the ejector device, a spindle element on which said cam is mounted to rotate freely thereon, said spindle element having a ratchet head, a belcrank latch element hingedly mounted on said cam and having a lug for releasable engagement with the ratchet head of said spindle element, a spring for releasably holding said latch element in such engagement, frictionally engaged driving means for said spindle element, manually operable stop means for arresting the cam in its rotation, said stop means comprising a lever element one end portion of which is swingable into and out of the path of the latch element on said cam, the opposite end portion of the lever constituting an operating handle therefor, means for marking the respective matrices during a period of rest in the travel thereof from the receiving magazine to the grinding element, said marking means comprising a rotary saw mounted on a constantly driven spindle, said spindle being mounted on a carrier movable laterally whereby the saw is brought into and out of contact with a positioned matrix, spring-actuated means for moving the spindle toward the trackage for the matrices, a controlling cam rotatable with said spindle element and peripherally engaged by an antifriction bearing element mounted on the saw spindle carrier to move laterally with the spindle, said controlling cam having a concentric high peripheral portion for holding the spindle with the saw away from the matrix trackage and a recessed portion permitting and limiting the movement of the spindle toward the matrix and the working engagement of the saw with a positioned matrix, and means for manually moving the saw spindle carrier away from the matrix trackage and releasably holding it in such position.

7. In a machine for reconditioning matrices, means including trackage and correlated feeding means for successively passing the matrices lineally with intermittent travel to a grinding element, means for individually marking the respective matrices during a period of rest in the travel thereof, said marking means comprising a rotary saw on a spindle mounted in a unitary assembly including a stationary supporting bracket, a carrier for the spindle hingedly mounted on said supporting bracket whereby the spindle is movable laterally toward and from the matrix trackage, said spindle having driving means constantly effective at any of the positions to which it is swung, a rotating cam controlling the posi-

tion of said spindle relative to the matrix trackage, said cam being peripherally engaged by an antifriction element on the spindle carrier, the cam having a concentric high portion holding the spindle away from the matrix trackage and a recess permitting and limiting the reverse movement of the spindle and the working engagement of the saw with the positioned matrix, a spring element acting upon the spindle carrier to constantly urge the spindle toward the matrix trackage, means for manually retracting the spindle carrier and releasably holding it with the spindle away from the matrix trackage and the saw out of engagement with the positioned matrix, and a manually operable stop device on said supporting bracket of said spindle carrier for arresting the operation of the matrix feeding means.

8. In the herein described machine for reconditioning matrices, a horizontal flat-surfaced annular grinding element, a dished carrier for said grinding element having an axially bored hub portion, a vertical driving shaft having a screw-threaded lower portion and a reduced upper portion fitted to the hub bore of the grinding element carrier, said shaft having a screw-threaded axial bore in its upper end portion, an internally threaded supporting and adjusting sleeve fitted on the screw-threaded portion of said driving shaft, a lock nut on said shaft to impinge the lower end of said sleeve, the upper end of the sleeve being formed with a headed enlargement and provided with a reduced bore to fit the reduced upper end portion of said driving shaft, the meeting ends of said sleeve and hub portion of the grinding element carrier being doweled so as to rotate together, the upper end portion of the driving shaft extending above the hub portion of the grinding element carrier, a superposed collar on the hub portion of said carrier surrounding and extending above the end portion of the driving shaft, a cap disk on said collar, said disk having a central opening, and a retaining screw inserted through said opening of the cap disk and fitted in the axial end bore of the driving shaft.

9. In a machine for reconditioning matrices, a grinding element over which the matrices are passed lineally with intermittent travel from trackage interposed between the grinding element and a receiving magazine, a reciprocatory ejector operating to move the matrices one at a time from the bottom of a pile thereof in the magazine, spring-actuated means for moving the ejector in the direction to discharge a matrix from the magazine, adjustable means for varying the matrix-ejecting stroke of the ejector, means for positively moving said ejector to a definite retracted position on each reciprocation thereof, said last named means comprising a rotating cam plate peripherally formed for engagement with a cooperative extension of said ejector, a driving spindle on which said cam plate is freely rotatable, clutch means for releasably interlocking said cam plate with said driving spindle whereby the plate is rotated by and with the spindle, friction brake means between the spindle and plate, manually operable means for disengaging said clutch means, matrix marking means comprising a rotary saw having a driving connection with said driving spindle, said saw being mounted for movement toward and from the matrix trackage between the magazine and grinding element, spring-actuated means for moving the saw toward the matrix trackage,

10 a peripherally formed controlling member rotatable by and with the aforesaid cam plate for moving and periodically holding said saw away from the matrix trackage and having provision for limiting the movement of the saw under the influence of its spring-actuated moving means toward the matrix trackage, manually operable means for retracting the saw from the matrix trackage and releasably holding it in retracted position, and adjustable delivery means including a drawer for receiving the dressed matrices from the grinding element and delivering them in a group from the machine, the drawer being impelled forwardly with a step-by-step movement 15 by actuating mechanism operated by said cam plate in timed relation to the operation of the matrix ejector, and the marking saw being actuated to and from marking position during a period of rest of the matrices in the line between the magazine and grinding element.

one end portion of said lever element being located in its normal position adjacent the path of said latch element on the cam element and moving into said path upon actuation of said lever element from its neutral position whereby to arrest said latch element and effect its disengagement from said ratchet head of the driving spindle, the opposite end portion of said lever element constituting an operating handle for the element.

12. In a machine for reconditioning matrices as herein described, and including a reciprocatory ejector device for moving the matrices one at a time from a pile thereof to the conditioning means of the machine, said ejector device being spring-impelled in the direction of movement to

5 transfer the matrices from the pile to the conditioning means, the impelling mechanism for said ejector device including a rocking lever and an adjustable stop element in the path of said rocking lever for variably limiting the movement of the lever on the matrix ejecting stroke of the ejector device, and means for positively moving said ejector device and returning it to a definite retracted position on each reciprocation thereof, said last named means including a rotating cam element against the periphery of which an anti-friction thrust member provided on the ejector device is held by the influence of the actuating spring of the ejector device during the major working travel of the cam periphery.

JOHN E. SHEAFFER.
